CENTRIFUGAL PIPE CASTING APPARATUS

Paul L. Arnold, Edgewater Park, N. J., assignor to
United States Pipe and Foundry Company, Bur-
lington, N. J., a corporation of New Jersey

Application December 30, 1933, Serial No. 704,614

4 Claims. (Cl. 22—65)

My invention relates to that class of centrifugal pipe casting apparatus in which a rotatable metallic pipe mold, preferably having a bell end, extends through a water box and is provided 5 at one end with a cylindrical driving sleeve secured to the end of the mold and extending back over the adjacent portion of the mold at a distance from the mold so as to form a water chamber between the sleeve and the mold, opening into 10 the water box, such as a sleeve, particularly when used in connection with the bell end of a mold, being preferably provided with gear teeth on that portion which extends beyond the wall of the water box to serve as a means in connection with 15 a gear train and driving motor for rotating the mold. As heretofore constructed, it has been found that at times and particularly in connection with the bell end of the mold, there was an insufficient circulation of water in the space between 20 the driving sleeve and the mold, with consequent defects in the cast pipe produced in the mold and injury to this portion of the mold and the object of my invention is to provide in such a structure for an ample and effective flow of 25 water over the end portion of the mold and the essential features of my invention consist in securing in place between the driving sleeve and the portion of the mold surrounded by the said sleeve a circular partition dividing this annular 30 space into two annular channels connected together at their inner ends, said circular partition extending along the mold to some distance beyond the free end of the sleeve secured to the mold and in providing at the end of one of the 35 annular passages formed between the partition and the mold and the partition and the driving sleeve an annular centrifugal pump rotating with the mold and so constructed as to create a flow of water from and to the water box progressively 40 through the conduit passages formed between the partition and the mold, thence into the annular passage formed between the partition and the driving sleeve and thence back to the water box, that is to say, in the same direction in which the 45 water would tend to flow under the influence of the centrifugal force applied to it as it rotates with the annular passages through which it passes.

The energy of the cooling action of the water 50 as it passes over the mold surface would depend partly on the volume of water and, to a large extent, upon its rate of flow in contact with the mold. The rate of flow could be partly determined by the cross-sectional area of the annular space between the circular partition and

the mold but both the volume and rate of flow are, to a great extent, dependent upon the capacity of the annular centrifugal pump and this, in turn is largely dependent upon the linear speed of its rotation and, particularly, in the case of molds of comparatively small diameter, this makes it important that the annular centrifugal pump element of the structure should be located at a considerable radial distance from the mold and, preferably, connected to the outlet 10 end of the annular passage, between the circular partition and the driving sleeve, this construction also having the advantage that it avails itself to the greatest extent of the tendency of the water to flow outwardly under the influence 15 of centrifugal force developed by its rotation in and with the annular passages through which it is drawn. It is, however, quite practicable and sometimes advantageous to connect the annular centrifugal pump with the outer end of the 20 passage formed between the circular partition and the mold, in which case it acts to force the water through the channels.

My invention will be best understood as described in connection with the drawings forming 25 a part of this specification, in which

Figure 1 is a sectional elevation of those portions of a centrifugal pipe casting machine to which my improvements are applicable and are applied taken on a vertical plane extending 30 through the center line of the centrifugal mold, the central portion of the water box and mold being broken away to enable the end portions to be shown on a larger scale.

Figure 2 is an enlarged fragmentary section 35 in which the driven end of the mold, the driving sleeve and the features which constitute my invention are shown on a larger scale.

Figure 3 is a sectional view partly in elevation, the section being taken as on the line 3—3 40 of Figs. 1 and 2.

Figure 4 is a fragmentary sectional view similar to Fig. 2, showing a modification and

Figure 5 is a sectional view on the line 5—5 45 of Fig. 4.

A indicates the water box which ordinarily forms a portion of a reciprocable carriage to which motion is imparted as by means of a cylinder and piston, as indicated at B. A¹ and A² indicate the opposite ends of the water box, 50 through which the mold ends extend and A³ a driving gear chamber formed at one end of the water box. At C, C, I have indicated the presence of the rear supporting rolls of two pairs of supporting rollers which support the mold in the 55

water box. D indicates the centrifugal mold having a bell end, indicated at D¹, on the outer end of which is secured a ring D² forming in effect a flanged extension of the bell end of the mold. E is a driving sleeve having an outwardly extending flange E¹, by means of which it is secured to the ring D² as by means of bolts indicated at E³. The body of the driving sleeve extends over the adjacent portion of the mold at a distance therefrom so as to form an annular water chamber between the driving sleeve and the mold which, at the open end of the sleeve, is in free communication with the water box. The driving sleeve extends through the wall A² of the water box and through the gear chamber A³ and this portion of the sleeve is, as shown, provided with gear teeth, as indicated at E⁴, which is engaged by gearing, as indicated at F actuated by a motor, as indicated at F¹. Packing is provided, as indicated at G, to form a water tight joint between the driving sleeve and the wall of the water box. At its spigot end the mold is formed with a sleeve extension, as indicated at H, adapted to form a water tight joint with the wall A¹ of the water box. To the extent above described, the apparatus shown in the drawings is a well known construction and forms no part of my invention.

J is a circular partition located in the annular chamber formed between the sleeve E and the bell end of the mold, dividing said annular chamber into two annular passages, one, K, located between the partition and the bell and the other, K¹, located between the partition and the sleeve, connected together at their inner ends, as indicated at K². The circular partition extends outwardly to some distance beyond the end of the sleeve E and, as shown in Figs. 1, 2, and 3, the outer end of the annular passage K¹ communicates with the water box through an annular centrifugal pump structure formed by an annular ring flange L secured to the end of the driving ring and an annular radial flange extending from the outer end of the circular partition and indicated at L¹ between which plates where they face each other, are secured impeller blades as indicated at M so as to constitute the structure an annular centrifugal pump. The annular plate L¹ and the circular partition J to which it is attached are secured in place, as shown, by bolts passing through the plate L¹ and screwing into the end of the driving sleeve J, as indicated at T.

In the modification illustrated in Fig. 4, N is an annular plate secured to rotate with the mold and located at some distance in front of the end of the circular partition J and O is an annular hood like extension from the end of the circular partition extending over the top of the annular plate N and down opposite the upper portion of said annular plate, as indicated at O¹, and between this partition and the hood and the upper part of the plate N are secured impeller blades P, constituting this portion of the structure a centrifugal pump which I have indicated at M¹. This structure provides a water conduit made up of the annular entrance opening Q, the annular chamber Q¹ lying below the impeller blades P, the space between the portion O¹ of the hood and the upper portion of the annular plate N and the space Q² lying beneath the hood and over the plate N and connecting with the outer end of the annular conduit K, thence through the passage K² into the annular passage K¹ and thence into the water box. In the construction shown, the hood O and the circular partition J secured to the hood or forming an extension of the hood, are

secured in place by being attached to brackets extending out from the water box, and indicated at R, and the inner end of the circular partition J is further aligned in its position within the driving sleeve by spacers as indicated at R¹. At S I have indicated the location in the hood of more or less radially arranged plates or vanes for counteracting any rotary movement which may be imparted to the water in passing through the centrifugal pump element.

In the construction shown in Figs. 1, 2, and 3, when the mold is in rotation, the annular centrifugal pump element connected, as described, with the outer end of the annular conduit K¹, creates a flow of water into the free end of the annular conduit K which passes first over the surface of the mold, thence outward through the passage K² into the annular passage K¹, thence longitudinally outward into the space lying beneath the centrifugal pump M and thence outward into the water box.

In the construction indicated in Fig. 4, the centrifugal pump M¹, when the mold is in rotation, draws in water from the water box through the annular opening Q and forces it into the curved annular passage indicated at Q², from which it passes to the annular conduit passage K, thence through the passage K² into the annular passage K¹ and thence into the water box.

It will be understood that in both modifications of my invention, the object to be had in view is to secure a proper degree of cooling of the portion of the mold lying within the driving sleeve by bringing about such a flow of water through the annular conduit passage K as will effect this result and the energy of flow through this passage will be determined partly by the cross-sectional area of the annular conduit K and partly by the total flow of water effected by the centrifugal pump and the capacity of the pump, so to speak, is largely dependent upon the linear speed with which its impeller blades move, their angular speed being, of course, that of the mold, and, therefore, the greater the diameter of the annular centrifugal pump the more effective it will be in creating a flow of water. It is also true, of course, that the capacity of the pump will depend, to a certain extent, upon the setting of the impeller blades.

Having now described my invention, what I claim as new and desire to secure by Letters Patent, is:

1. In a centrifugal pipe casting machine comprising a water box, a metallic mold extending through the water box, having attached to its end a driving sleeve extending over and spaced away from the adjacent portion of the mold and extending through a wall of the water box with its open end lying within the water box and means for rotating the mold connected to that portion of the driving sleeve which lies outside of the wall of the water box, improved means for bringing about a flow of water over the portion of the mold lying within the driving sleeve which consists in securing in the space between the driving sleeve and the mold a circular partition dividing said space into two annular passages connected together at their inner ends and in locating at the outer end of one of said annular passages an annular rotary pump connected to revolve with the mold and operative when the mold is in rotation to create a flow of water from and to the water box and progressively through the inner and outer annular passages formed by

the circular partition between it and the mold and between it and the driving sleeve.

2. Apparatus as called for in claim 1, in which the rotary pump consists of a centrifugal pump located at the outer end of the outer annular passage.

3. Apparatus as called for in claim 1, in which an outwardly extending annular passage is provided at the outer end of the outer annular passage formed between the circular partition and

the driving sleeve and in which impeller blades are so located in said outwardly extending annular passage as to constitute in connection with said passage a centrifugal pump.

4. Apparatus as called for in claim 1, in which a metallic mold is provided with a bell end and the driving sleeve is secured to the end of the bell end of the mold. 5

PAUL L. ARNOLD. 10
